(57) **CLAIM**

I claim the ornamental design for a rear side molding for a model vehicle, as shown and described.

DESCRIPTION

FIG. 1 is a top, left, front perspective view of a rear side molding for a model vehicle;

FIG. 2 is front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, right, rear perspective view; and,

FIG. 9 is a top, left, front perspective environmental view.

In the drawings, the broken line showing of features of the rear side molding for a model vehicle illustrate portions of the rear side molding for a model vehicle that form no part of the claimed design; whereas, the broken line showing of the environmental view depicts environmental subject matter and is provided for the purposes of illustrating environmental structure and context.

In addition, in the drawings the representative front side molding depicted is a left rear side molding. The right rear side molding is a mirror image of the left rear side molding.
